UNITED STATES PATENT OFFICE

HUGO E. GRIESHABER, OF NEW LONDON, CONNECTICUT, ASSIGNOR TO ELECTRIC BOAT COMPANY, OF GROTON, CONNECTICUT, A CORPORATION OF NEW JERSEY

SUBMARINE BOAT

Application filed April 11, 1928. Serial No. 269,049.

This invention relates to submarine boats, and more particularly to a submarine boat provided with salvage or refuge compartments and means associated therewith for blowing out the other compartments and tanks of the boat in case of accident or collision resulting in flooding to an undesirable extent, such other compartments and tanks.

It is the present practice in constructing submarine boats to divide the hull of the boat into compartments and tanks by means of suitable bulk heads, such compartments being watertight. Certain of the compartments thus provided are usually constructed in such manner as to withstand deep submergence pressures in case the body of the boat becomes flooded, these compartments having water-tight doors opening outwardly thereof and being known as salvage or refuge compartments. In accordance with my invention I provide, in the refuge compartments, air manifolds to which air is supplied under pressure in a suitable manner from a compressed air supply on the submarine boat or from a salvage ship. Air pipes extend from these manifolds into the other compartments and tanks of the boat, there being a separate pipe for each compartment or tank and the pipes of each manifold being separate from the pipe of the other manifolds. I also provide means for indicating in each refuge compartment the condition of the other compartments or tanks of the boat. A further object of my invention is to so dispose the various pipes and air lines as to reduce to a minimum the possibility of injury thereto in case of collision. Further objects and advantages will appear from the detail description.

40 In the drawings:

Fig. 1 is a semi-diagrammatic sectional view of a submarine boat in accordance with my invention, taken fore and aft of the hull and substantially in the plane of the 45 keel;

Fig. 2 is a view similar to Fig. 1 showing the air pipes from the after air manifold only, the air pipes from the other manifolds being omitted for the sake of clearness;

50 Fig. 3 is a view like Fig. 1 showing the

test pipes from the after refuge compartment only, the other pipes being omitted for clearness;

Fig. 4 is a view like Fig. 1 showing the gage lines from the after refuge compartment only, the other pipes and associated parts being omitted for the sake of clearness;

Fig. 5 is a view like Fig. 1 showing the common air line connecting the air manifolds and the associated parts, the other pipes being omitted for clearness;

Fig. 6 is a detail of one of the gauges and its associated lines of Fig. 4;

Fig. 7 is a transverse section through the control operating compartment of the boat taken substantially on line 7—7 of Fig. 1, the superstructure and associated parts being omitted;

Fig. 8 is a transverse section of the boat taken substantially on line 8—8 of Fig. 1 through the torpedo compartment, the superstructure and associated parts being omitted;

Fig. 9 is a detail view of the aft air manifold and associated air pipes and control valves therefor.

My invention is applied to a submarine boat including a hull 1, the interior of which is divided by suitable bulkheads into a motor compartment 2, engine compartment 3, after battery compartment 4, central operating compartment 5, forward battery compartment 6, torpedo compartment 7, ballast tanks 8, and forward and aft fuel tanks 9 and 10, respectively. The compartments, 2, 5 and 7, constitute the after refuge compartment, the midship refuge compartment and the forward refuge compartment, respectively. The bulkheads at the ends of these compartments are of such construction that each refuge compartment is particularly adapted to withstand deep submergence pressure.

An air manifold 11 is provided in each of the refuge compartments. A plurality of air pipes 12 extend from each of the manifolds in each of the refuge compartments and open into the other compartments and tanks of the boat, these air pipes being separate from each other and there being provided one pipe for each tank and compartment, the air pipes

from each manifold being separate and distinct from the air pipes from the other manifolds. Each air pipe 12 is controlled by a valve 13 in the manifold 11 (Fig. 9). The 5 stem 14 of this valve extends through a stuffing box 15 and is provided, adjacent the manifold, with a hand wheel 16 secured thereon. Stem 14 of valve 13 extends through the upper portion of hull 1 and is provided at 10 its upper end with a hand wheel 17 disposed within the superstructure 18 of the boat. A suitable stuffing box structure is provided for the valve stem 14 and an opening is provided through the superstructure to permit access 15 to the hand wheel 17 by a diver exterior of the hull. In this manner, the admission of air to the pipe 12 may be controlled either exteriorly or interiorly of the hull of the boat. The manifold 11 is also provided with 20 an air outlet nipple 19a opening into the compartment in which the manifold is located. This nipple is controlled by a suitable valve 20a. This provides means whereby the air supply in the compartment can be 25 readily replenished from the manifold, as required. I also provide each of the air manifolds in the compartments 2 and 7 with an air supply pipe 19 which extends through the upper portion of the hull 1 and is provided 30 with a suitable control valve 20 accessible through a suitable opening in the superstructure 18. This air supply pipe 19 is adapted for connection to an air hose from a salvage or rescue ship whereby air under 35 pressure may be supplied to the manifold. A similar air supply pipe may be provided for the manifold in the central compartment 5 if desired. Referring more particularly to Fig. 5, I preferably provide in each refuge 40 compartment a bank of air flasks 21, which are suitably connected to a branch pipe 22 provided with a reducing valve 22a of suitable type and having connection with a pipe 23 which is connected to an air line 24 common to all of the air manifolds. Suitable 45 valves 25 in the pipe 22 control communication between this pipe and the air flasks 21, and a valve 26 in the pipe 23 controls communication between this pipe and air manifold 11.

By properly manipulating the valves air under pressure may be supplied from one or more of the banks of air flasks to any selected one of the air manifolds.

55. It is to be particularly noted that the common air line 24 is disposed at the lower portion of the hull 1. I consider this of importance in view of the fact that a submarine boat, in case of collision, is seldom injured 60 at the lower portion of the hull, any injury which the hull may suffer being usually confined to the portion above the center line thereof. It is vital that the air line 24 be protected against injury and I accomplish this by disposing the air line in the manner

illustrated and described. It is also to be particularly noted that the air pipes 12 are disposed below the center line of the hull and, consequently, danger of injury to these air pipes is reduced to a minimum. This is 70 important as these pipes should remain intact, in case of collision, in order that the tanks and the compartments of the boat may be blown out to increase the buoyancy thereof sufficiently to permit the boat to rise 75 to the surface.

Referring more particularly to Fig. 3, I provide a plurality of test pipes 27 which extend from each of the refuge compartments and open into the same, each of these pipes being controlled by a suitable valve 28 therein adjacent its open end. The pipes 27 extend into the other compartments and tanks of the boat, each of these pipes being provided with an arcuate head 29 (Fig. 7), shaped to conform to the curvature of the hull 1 and provided at each end with an arm 30 extending fore and aft of the hull and disposed adjacent the top of the tank or compartment, into which the said pipe extends. The head 29 may be omitted from certain of these pipes which extend directly into the upper portion of the tank or compartment, as will be apparent from Fig. 3. The ends of the pipes remote from the refuge compartment from which such pipes extend are closed, and the pipes are closed throughout their lengths. I provide one of these pipes for each tank or compartment and such test pipes may be connected to a single line or pipe which is common to all of the refuge compartments. Normally the valves 28 are closed. The elements of the test pipes disposed in the upper portion of the compartments or tanks are preferably of relatively light construction so as to be readily broken in the case of injury to the upper portion of the hull 1 by collision, or if the upper part of the hull is damaged by a depth bomb or other means. The test pipe in the injured compartment or tank is thus broken so as to admit water thereto. By opening the valve 28 the operator in any one of the refuge compartments can readily determine whether the tank or compartment into which such test pipe extends has been injured, as the presence of water in the test pipe, which would be discharged therefrom upon opening of the valve 28, indicates that the upper portion of this compartment or tank has been punctured 115 and that it cannot, therefore, be effectively blown out.

Referring more particularly to Fig. 4 of the drawings, each of the refuge compartments is provided with a gauge board 31 upon which are mounted gauges 32 of suitable type (Fig. 6). Each of these gauges is connected by a line 33 to an operating device 34 suitably mounted in one of the compartments or tanks of the boat. The operat- 125 130

ing device may be of any suitable or preferred type, that shown including a sylphon 35 to which is connected one arm of a lever 36 pivoted at 37 and provided at its other end with a suitable float 38. When the compartment or tank in which the device 34 is mounted is empty the float 38 is in its lowered position and the sylphon 35 is retracted or compressed and actuates the gauge 32, 5 through the connecting line 33, to move the indicator point of this gauge "empty" position. In the event that the compartment or tank is flooded, the float 38 is raised and extends the sylphon 35 actuating the gauge 32 to move the indicator point thereof to the "flooded" position. In this manner the men in any one of the refuge compartments can readily determine whether any other selected one of the 10 compartments or tanks of the boat have been injured in such manner as obviate blowing the water out of such compartments or tanks and they can also readily determine which compartments or tanks of the boat are 15 flooded. This is of importance as avoiding the wasting of any air in an attempt to blow out compartments or tanks which either are not flooded or are damaged in such manner as to render it impracticable to blow them 20 out with the compressed air supply available on the boat. These gauges also serve to indicate when a tank has been completely blown out and is empty, thus avoiding any waste of air by continued blowing of a tank 25 or compartment after the water has been blown therefrom.

Referring more particularly to Figs. 7 and 8, each compartment of the boat is provided with a drain opening 39 extending from the 30 lower portion thereof through the bottom of the hull 1, this opening being normally closed by a suitable check valve 40 which is urged in closing direction by a spring 41 associated therewith in a known manner, or 35 in any other suitable manner. Each of the tanks is also provided with a drain opening extending through the bottom of the hull and normally closed by a valve 42 similar to the valve 40. Under normal conditions the 40 valves 40 and 42 remain closed. In the event of the boat becoming disabled due to collision or other cause, and sinking to the bottom, the men enter the refuge compartments and the doors of such compartments 45 are immediately closed. The men in the compartments determine by means of the test pipes and the gauges which of the tanks and compartments of the boat can be blown out. Such tanks and compartments are then 50 blown out by admitting air under pressure thereto through the pipes 12. During blowing out of the tanks or compartments the valves 40 and 42 are unseated and forced into open position as illustrated in Fig. 7. After 55 blowing out of the tanks and compartments

and lowering of the air pressure therein, the drain valves are automatically closed by their associated springs, and are then held in closed position by the preponderance of the water pressure exterior of the hull. In this 70 manner, the buoyancy of the hull can be increased to such an extent as to enable the boat to free itself from the bottom and rise to the surface where repair of the boat may be effected.

In the event that the air supplied by the banks of air flasks is insufficient to accomplish blowing out of the flooded compartments and tanks of the boat, a diver from a salvage boat, which may be either a surface boat or a submarine boat, is lowered to the disabled boat and connects an air line to the air supply pipe 19, after which he opens the valve 20 admitting the air to the air manifold, and the men in the refuge compartments then open the valves of the air pipes 12 to blow out the various compartments and tanks which may be flooded, in the manner previously described. Instead of the crew 80 on the disabled boat blowing out the various tanks and compartments, this may be done by the diver. In some cases this is preferable, as the diver can tell the lay of the boat, the condition of the bottom, etc.; and can determine which part of the boat should 85 rise first, or whether the boat should rise in horizontal position. He can then blow out the proper compartments and tanks in proper order to effect the desired result.

When the boat is operating submerged, the 90 valves 25 are open so that air from the banks of air flasks is immediately available at any of the air manifolds. The valves 13 of the air pipes 12, as well as the valves 15 of the branch pipes 14, and the valves 28 of the test pipes 27, are all normally closed. In the event that there are no men alive in the refuge compartment, as when the men have 95 been unable to reach such compartment, the diver, after attaching the air hose to the air supply pipe 19, opens the valves 13 so as to admit compressed air to the air pipes 12 and blow out the compartments and tanks of the boat into which these pipes open, thus rendering the boat sufficiently buoyant to 100 rise to the surface. Which of the compartments and tanks are blown out, and the order in which this is done, will depend upon the position in which it is desired to raise the boat, as above explained.

As previously noted, the air line 24, as well 110 as the air pipes 12, are all disposed below the center line of the hull so as to be protected against injury in case of collision or damage to the upper portion of the hull from other cause. It is also to be noted that the indicating or gauge lines 33 are disposed below the center line of the hull so as to be 115 protected against injury. As in the case of the air pipes and test pipes, each of the refuge 120

compartments is provided with a separate gauge and associated gauge line for each of the other compartments and tanks of the boat.

What I claim is:—

5. 1. In a submarine boat comprising a hull provided with compartments and tanks having drain valves, certain of said compartments being refuge compartments, air manifolds in the refuge compartments, air pipes extending from the respective manifolds and opening into the compartments and tanks, the pipes from the manifolds being independent of each other and there being a separate pipe for each compartment and each tank, means for supplying air under pressure to the manifolds, and means for indicating in each of the refuge compartments the condition of each of the other compartments and tanks. 70
10. 2. In a submarine boat comprising a hull provided with compartments and tanks having drain valves, certain of said compartments being refuge compartments, air manifolds in the refuge compartments, air pipes extending from the respective manifolds and opening into the compartments and tanks, the pipes from the manifolds being independent of each other and there being a separate pipe for each compartment and each tank, means for supplying air under pressure to the manifolds, and means for indicating in each of the refuge compartments the condition of each of the other compartments and tanks. 75
15. 3. In a submarine boat comprising a hull provided with compartments and tanks having drain valves, certain of said compartments being refuge compartments, air manifolds in the refuge compartments, air pipes extending from the respective manifolds and opening into the compartments and tanks, the pipes from the manifolds being independent of each other and there being a separate pipe for each compartment and each tank, means for supplying air under pressure to the manifolds, and means for indicating in each of the refuge compartments the condition of each of the other compartments and tanks. 80
20. 4. In a submarine boat comprising a hull provided with compartments and tanks having drain valves, certain of said compartments being refuge compartments, air manifolds in the refuge compartments, air pipes extending from the respective manifolds and opening into the compartments and tanks, the pipes from the manifolds being independent of each other and there being a separate pipe for each compartment and each tank, means for supplying air under pressure to the manifolds, and means for indicating in each of the refuge compartments the condition of each of the other compartments and tanks. 85
25. 5. In a submarine boat comprising a hull provided with compartments and tanks having drain valves, certain of said compartments being refuge compartments, air manifolds in the refuge compartments, air pipes extending from the respective manifolds and opening into the compartments and tanks, the pipes from the manifolds being independent of the pipes from the other manifolds, and valves controlling the pipes and operable both from within the respective refuge compartments and exteriorly of the hull. 90
30. 6. In a submarine boat comprising a hull provided with compartments and tanks, certain of said compartments being refuge compartments, air manifolds in the refuge compartments, pipes connected to the respective manifolds and opening into the compartments and tanks, the pipes from each manifold being independent of the pipes from the other manifolds, and valves controlling the pipes and operable both from within the respective refuge compartments and exteriorly of the hull. 95
35. 7. In a submarine boat comprising a hull provided with compartments and tanks, certain of said compartments being refuge compartments, air manifolds in the refuge compartments, pipes connected to the respective manifolds and opening into the compartments and tanks, the pipes from each manifold being independent of the pipes from the other manifolds, and valves controlling the pipes and operable both from within the respective refuge compartments and exteriorly of the hull. 100
40. 8. In a submarine boat comprising a hull provided with compartments and tanks, certain of said compartments being refuge compartments, air manifolds in the refuge compartments, pipes connected to the manifolds and opening into the compartments and tanks, means for connecting the manifolds to a source of supply of air under pressure exterior of the hull, and valves controlling the pipes, said valves having operating members extending into the refuge compartments and also extending through the hull whereby the valves are operable both from within the refuge compartments and exteriorly of the hull. 105
45. 9. In a submarine boat comprising a hull provided with compartments and tanks, air manifolds in certain of said compartments, pipes connected to the manifolds and opening into the compartments and tanks, valves controlling the pipes and operable exteriorly of the hull, and means for connecting the manifolds to a source of supply of air under pressure exterior of the hull. 110
50. 10. In a submarine boat comprising a hull provided with compartments and tanks, certain of said compartments being refuge compartments, means controlled from the refuge compartments for supplying air under pressure to said compartments and tanks, means for indicating in each of the refuge compartments whether each of the other compartments and tanks is flooded, and means for indicating in each of the refuge compartments whether each of the other compartments and tanks is punctured. 115
55. 11. In a submarine boat comprising a hull provided with compartments and tanks, certain of said compartments being refuge compartments, means controlled from the refuge compartments for supplying air under pressure to said compartments and tanks, means for visually indicating in each of the refuge compartments whether each of the other compartments and tanks is punctured. 120
60. 12. In a submarine boat comprising a hull provided with compartments and tanks, certain of said compartments being refuge compartments, means controlled from the refuge compartments for supplying air under pressure to said compartments and tanks, means for visually indicating in each of the refuge compartments whether each of the other compartments and tanks is punctured. 125
65. 13. In a submarine boat comprising a hull provided with compartments and tanks, certain of said compartments being refuge compartments, means controlled from the refuge compartments for supplying air under pressure to said compartments and tanks, means for visually indicating in each of the refuge compartments whether each of the other compartments and tanks is punctured. 130

In witness whereof, I hereunto subscribe my name this 6th day of April, 1928.

HUGO E. GRIESHABER.
